UNITED STATES PATENT OFFICE

134,502

DESIGN FOR AN ARMORED TANK TRACK COUPLER

William F. Bromm, Chicago, Ill.

Application July 27, 1942, Serial No. 107,716

Term of patent 3½ years

To all whom it may concern:

Be it known that I, William F. Bromm, a citizen of the United States of America, residing at 2602 South Halsted Street, Chicago, Illinois, have invented a new, original, and ornamental Design for an Armored Tank Track Coupler, of which the following is a specification, reference being had to the accompanying drawing forming a part thereof.

Fig. 1 is a front elevational view, Fig. 2 is a rear elevational view, and Fig. 3 is a side elevational view of an armored tank track coupler embodying my new design.

I claim:

The ornamental design for an armored tank track coupler, substantially as shown.

WILLIAM F. BROMM.
